UNITED STATES PATENT OFFICE

CURTIS L. HOWSE, OF DETROIT, MICHIGAN, AND NORMAN L. SNOW, OF NEW CANAAN, CONNECTICUT, ASSIGNORS TO DIAMOND POWER SPECIALTY CORPORATION, OF DETROIT, MICHIGAN, A CORPORATION OF MICHIGAN

BOILER CLEANER

Application filed January 18, 1926, Serial No. 82,131. Renewed November 4, 1931.

The invention relates to boiler cleaners and has for its object to provide an improved device for cleaning boilers of the type employing discharge of a cleaning fluid under pressure.

5 Referring to the accompanying drawings in which like reference characters indicate corresponding parts;

Figure 1 is a transverse sectional view 10 through the boiler cleaner showing the same applied to a locomotive boiler;

Figure 2 is a sectional view in elevation along 2—2 of Figure 1;

15 Figure 3 is a detail elevational view of the blower body portion or blower head;

Figure 4 is an elevational view at the nozzle end of the body portion;

Figure 5 is an elevation view at the opposite end thereof;

20 Figure 6 is a detail sectional view along 6—6 of Figure 1;

Figure 7 is a view corresponding to Figure 1 illustrating a modified construction of boiler cleaner;

25 Figure 8 is a sectional elevation view along 8—8 of Figure 7; and

Figure 9 is a view similar to Figure 7 showing a lubricating attachment associated with the boiler cleaner.

30 In the drawings reference characters 10 and 11 indicate the outside and inside walls respectively of a side wall water leg 12 of a locomotive boiler, 13 representing the tube sheet and 14 the boiler tubes. 15 is a nipple

35 expanded in the water leg 12 and forming an opening transversely therethrough. 16 represents a casing relatively stationary with respect to the nipple 15 and provided with a portion 17 housed within the nipple. 18 represents the blower body portion or blower head rotatable within the nipple 15 and provided with the axial bore 19 receiving the forward end of the rod 20. This rod is fixed

40 with the body portion 18 as by a set screw 21, the rod having a bearing in the casing portion 22. The forwardly extending portion 17 is provided with an annular shoulder 23 forming a bearing at 24 for the rotatable blower head 18.

45 50 The casing 16 is provided with a cleaning

fluid inlet at 25, 26 being a passage for conducting the cleaning fluid from the inlet longitudinally of the blower to a port 27, best shown in Figure 2. 28 is an inlet for a cooling fluid such as air, 29 representing a passage for conducting such fluid from the inlet to a port 30 as shown in Figure 2.

As best shown in Figures 3, 4 and 5, the blower head or body portion 18 is formed with a plurality of longitudinally spaced radially extending walls 31, adjacent walls thus forming cleaning fluid conducting passages extending longitudinally of the body portion. As shown in the drawings, six of these passages have been provided and respectively designated by reference characters M', M², M³, M⁴, M⁵ and M⁶ and their outer ends form ports. These passages are of a tortuous character and may be formed in concentric spirals longitudinally of the blower head 18. N', N², N³, N⁴, N⁵ and N⁶ are cleaning fluid discharge nozzles respectively communicating with the passages M', M², M³, M⁴, M⁵ and M⁶, the nozzles being directed for discharging jets of cleaning fluid toward the tube sheet 13 and boiler tubes 14, the nozzles varying in angularity with respect to the axis of the blower head as shown in Figures 1 and 4 so that as the blower head is rotated the nozzles will successively direct jets of cleaning fluid across the tube sheet 13. In this manner any desired portion of the tube sheet can be cleaned for a predetermined amount of rotation of the blower head.

45 The nozzles and walls 31 are preferably cast integrally to form the blower head 18. In order to provide an inclosure radially of the spiral passages, a sleeve 32 is provided which in assembling the blower head may be moved into the position shown in Figure 1 by sliding the same longitudinally of the blower head in contact with the outer extremities of the walls 31.

For rotating the blower head 18 a worm wheel 33 is provided fixed to the rear end of the rod 20 and rotatable within the worm gear casing 34. 35 is a worm meshing with the worm wheel 33, the former being mounted on a shaft 36 which may be extended to any convenient point of operation such as the

cab of the locomotive (not shown). 37 is an anti-friction thrust bearing for taking the forward thrust of the rod 20 produced by the longitudinal component of the force of 5 the cleaning fluid discharged from the nozzles.

In operation of the boiler cleaner as thus far described, when it is desired to clean the boiler tubes 14 and flue sheet 13 cleaning fluid 10 is admitted to the inlet 25 and passage 26 whence it passes to the inlet port 27. In order to rotate the blower head 18 to successively register the spiral passages and nozzles communicating therewith with this port 15 27, the rod 36 is rotated, which through the worm 35 and worm wheel 33 produces rotation of rod 20 and blower head 18. With the parts positioned as shown in Figure 1, the passage M⁴ is in communication with the 20 port 27 so as to supply cleaning fluid from the passage 26 through passage M⁴ to nozzle N⁴ which is directed toward the tube sheet 13. As the adjacent passage M⁵ is brought 25 to register with port 27 by rotation of the blower head 18 the corresponding nozzle N⁵ will be directed toward the tube sheet 13 and will discharge a jet of cleaning fluid at an angle varying slightly with the angle of discharge of the nozzle N⁴. The latter nozzle 30 will then have its passage M⁴ rotated beyond the port 27 and the supply of cleaning fluid will in this manner be cut off. By varying the circumferential length of the port 27 any 35 number of the nozzles may be supplied with cleaning fluid from passage 26 at the same time and in this same manner the sweep of the cleaning fluid jets may be readily determined. As the passages are rotated out of registration with the port 27 they are successively brought into registration with the 40 port 30, thus admitting the cooling fluid from the inlet 28. The cooling fluid will be conducted through the passages and will be discharged from the respective nozzles thus serving 45 to maintain the passages and nozzles at a relatively low temperature.

The rod 20 may be provided with an axial bore 38 terminating rearwardly in a nipple 39, the latter passing outwardly through a 50 suitable opening in the worm gear casing 34. Threaded on this nipple is a lubricant containing cup 40, the latter being fixed to the nipple 39 by a set screw 41. 42 is a cap for the cup 40 permitting replenishing of the 55 latter with a suitable lubricant. 43 is a piston fitting closely in the cup 40 and provided with a threaded rod 44 integral therewith. This rod is formed with a T-head 45 which operates in the guides 46 formed in 60 the opposed ends of the brackets 47 and 48 fixed with the casing 34 by fasteners 49. As the rod 20 is rotated as aforesaid, the cup 40 will be rotated therewith. The piston 43 by reason of the T-head 45 and threaded connection 50 between the rod 44 and cover 42, will

be fed axially and inwardly of the cup 40 to force the lubricant from the cup into the passage 38. The rod 44 is provided with an unthreaded portion 51 of relatively small diameter so that the rod 44 will free itself 70 from engagement with the cover 42 as the piston 43 approaches the bottom of the cup 40. From the passage 38 the lubricant may be distributed through the radial passages 52 for lubricating the bearing between the portion 22 of the casing and the rod 20. 53 is a passage for conducting lubricant from the passage 38 to the anti-friction thrust bearing 37. In order to supply lubricant to the bearing 24 between the blower head 18 and the annular shoulder 23, the main lubricant supply passage 38 is provided with a radially extending passage 54 for supplying lubricant to the passage 26 at a point adjacent the 80 port 27. The passage of the cleaning fluid along passage 26 and through port 27 will pick up the lubricant from passage 54 and conduct the same to the bearing 24.

In this manner lubricant is supplied to any 90 desired point, the supply being automatically controlled and fed by operation of the boiler cleaner.

Referring to Figures 7, 8 and 9, a slightly modified construction of boiler cleaner is shown in which the rod 20 is provided with a piston 55 operable in a cylinder 56. 57 is a conduit for supplying cleaning fluid from the inlet 25 to act on the piston 55 whenever the cleaning fluid is being supplied to the blower head. Thus, the blower head is balanced with respect to forces acting longitudinally of the blower head since the thrust longitudinally outwardly on the blower head caused by the pressure of the cleaning fluid is substantially balanced by a counter inward longitudinal thrust on the blower head by reason of the action of the cleaning fluid on piston 55. The effective area of the piston 55 may thus be made to substantially balance the blower head against longitudinal thrusts. The thrust bearing 37 shown in Figure 7 may be entirely dispensed with in this construction, but may be provided for action in the event of failure of the piston 55. The lubricant cup 40 may be associated with this modified form of blower element by extending the lubricant conduit through the piston 53 and the chamber 56 as clearly shown in Figure 9 of the drawings.

In both of the boiler cleaner constructions shown in Figures 1 and 7 the discharge of cleaning fluid from the nozzles will result in a reaction force which may be resolved into two components, one longitudinal of the blower head and the other transverse thereof. The reaction component which acts longitudinally of the blower head may be balanced by the piston 55 as shown in Figure 7, or absorbed by the thrust bearings 37 as shown in Figures 1 and 7. Referring to Fig-

ure 7, I have illustrated the other of these components, namely, the reaction component which acts transversely of the longitudinal axis of the blower head by reference character R. Since the blower head 18 has its bearing at 24, the moment acting on the blower head by reason of the force R may be represented by $R \times D$. The blower head illustrated in Figures 1 and 7 is adapted to be balanced against this moment by reason of the force of the cleaning fluid entering the spiral passages from the port 27, this force acting longitudinally of the blower head being represented by F. The force F is determined by the product of the cleaning fluid pressure times the area of the port 27, the pressure against area of the port 27 being effective because of the fact that the passages are not extended in a straight line longitudinally of the blower head, but are arranged tortuously or spirally as shown in the drawings. Thus the blower head is subjected to a moment by reason of the force F, this moment being represented by $F \times L$ (in which L is the distance of the point of application of force F to the center of movements) which acts in opposition to the moment $R \times D$ and to substantially counter balance this moment. Thus by properly proportioning these parts the blower head may be balanced against forces acting transversely of the blower head.

What we claim as our invention is:—

1. A boiler cleaner comprising a casing having a cleaning fluid inlet and a cleaning fluid supply port, a blower head having a plurality of ports, means for moving the blower head relative to the casing for successively supplying cleaning fluid from said supply port to said blower head ports, and a plurality of nozzles communicating through tortuous passages with said blower head ports respectively, the said passages being so arranged as to conduct the cleaning fluid in such a course that the latter resists the reaction of the cleaning fluid escaping from the nozzles.

2. A boiler cleaner comprising a casing having a cleaning fluid inlet and a cleaning fluid supply port, a blower head having a plurality of ports, means for moving the blower head relative to the casing for successively supplying cleaning fluid from said supply port to said blower head ports, and a plurality of nozzles communicating through spiral passages with said blower head ports respectively, the said passages being so arranged as to resist the reaction of the steam escaping from the nozzles.

3. A boiler cleaner comprising a casing having a cleaning fluid inlet and a cleaning fluid supply port, a blower head having a plurality of ports, means for rotating the blower head relative to the casing for successively supplying cleaning fluid from said

supply port to said blower head ports, and a plurality of nozzles communicating through passages spirally formed around the axis of said rotation with said blower head ports respectively, the said passages being so arranged as to conduct the cleaning fluid in such a course that the latter resists the reaction of the cleaning fluid escaping from the nozzles.

4. A boiler cleaner comprising a casing having a cleaning fluid inlet and a cleaning fluid supply port, a blower head having a plurality of ports, means for moving the blower head relative to the casing for successively supplying cleaning fluid from said supply port to said blower head ports, and a plurality of nozzles communicating through tortuous passages with said blower head ports respectively, said nozzles varying in angularity with respect to the axis of the blower head and said passages being so arranged as to resist the reaction of the steam escaping from the said nozzles.

5. A boiler cleaner comprising a casing having a cleaning fluid inlet and a cleaning fluid supply port, a blower head having a plurality of ports, means for rotating the blower head relative to the casing for successively supplying cleaning fluid from said supply port to said blower head ports, and a plurality of nozzles communicating through passages spirally formed around the axis of said rotation with said blower head ports respectively, said passages being so arranged as to conduct the cleaning fluid in such a course that the latter resists the reaction of the cleaning fluid escaping from the nozzles, said nozzles varying in angularity with respect to the axis of the blower head.

6. A boiler cleaner comprising a casing having a cleaning fluid inlet and a supply port, a blower head having a plurality of discharge nozzles and spirally extending cleaning fluid supply passages therefor, and means for rotating the blower head for causing successive registration of the said cleaning fluid supply passages with said supply port, said spiral passages being formed concentrically with respect to the axis of rotation of the blower head.

7. A blower comprising a plurality of nozzles adapted to discharge cleaning fluid adjacent parts of a boiler to be cleaned and having passages respectively communicating with said nozzles for conducting cleaning fluid thereto from a source of supply, said passages being formed spirally about a common axis.

8. A rotatable blower comprising a plurality of nozzles adapted to discharge cleaning fluid adjacent parts of a boiler to be cleaned and having passages respectively communicating with said nozzles for conducting cleaning fluid thereto from a source of supply,

said passages being formed spirally around the axis of rotation of the blower.

5. A rotatable blower comprising a plurality of nozzles adapted to discharge cleaning fluid adjacent parts of a boiler to be cleaned and having passages respectively communicating with said nozzles for conducting cleaning fluid thereto from a source of supply, said passages being formed spirally around the axis of rotation of the blower, said nozzles varying in angularity with respect to said axis of rotation.

10. A blower comprising a nozzle adapted to discharge cleaning fluid adjacent parts of a boiler to be cleaned and having a passage communicating with the nozzle for conducting cleaning fluid thereto from a source of supply, said passage being formed spirally and being so arranged that the cleaning fluid as it flows through the passage creates a force which tends to balance the reaction of the cleaning fluid escaping from said nozzle.

11. A boiler cleaner comprising a casing having a cleaning fluid inlet and a supply port, a blower head having a plurality of ports, means for rotating the blower head for successively supplying cleaning fluid from said supply port to said blower head ports, a plurality of nozzles carried by the blower head adapted upon rotation of the blower head to supply jets of cleaning fluid successively toward predetermined parts of the boiler to be cleaned, said blower head having a plurality of spirally arranged cleaning fluid conducting passages respectively connecting the said nozzles and blower head ports, each of said passages being so arranged that the cleaning fluid as it flows through the passage creates a force which tends to resist the reaction of the cleaning fluid escaping from the nozzle of the passage and means for automatically preventing the supply of cleaning fluid to such nozzles as are not directed to a predetermined portion of the boiler.

45 12. A boiler cleaner comprising a casing having a cleaning fluid inlet and a cleaning fluid supply port, a blower head having a plurality of ports, means for moving the blower head relative to the casing for successively 50 supplying cleaning fluid from said supply port to said blower head ports, a plurality of nozzles communicating through tortuous passages with said blower head ports respectively, and means for introducing a cooling fluid 55 to at least one of the said tortuous passages when their respective blower head ports are not in registration with said supply port.

13. A boiler cleaner comprising a casing having a cleaning fluid inlet and a cleaning fluid supply port, a blower head having a plurality of ports, means for moving the blower head relative to the casing for successively supplying cleaning fluid from said supply port to said blower head ports, a plurality of nozzles communicating through spi-

ral passages with said blower head ports respectively, and means for introducing a cooling fluid to at least one of the said spiral passages when their respective blower head ports are not in registration with said supply port.

14. A boiler cleaner comprising a casing having a cleaning fluid inlet and a cleaning fluid supply port, a blower head having a plurality of ports, means for rotating the blower head relative to the casing for successively supplying cleaning fluid from said supply port to said blower head ports, a plurality of nozzles communicating through passages spirally formed around the axis of said relative rotation, and means for introducing a cooling fluid to at least one of the said spiral passages when their respective blower head ports are not in registration with said supply port.

15. A boiler cleaner comprising a casing having a cleaning fluid inlet and a cleaning fluid supply port, a blower head having a plurality of discharge nozzles and spirally formed cleaning fluid conducting passages for said nozzles, and means for moving the blower head relative to the casing for successively supplying cleaning fluid from said supply port through said passages to said discharge nozzles, and means for introducing a cooling fluid to at least one of the said spiral passages when their respective blower head ports are not in registration with said supply port.

16. A boiler cleaner comprising a casing having a cleaning fluid inlet and a supply port, a blower head having a plurality of ports, means for rotating the blower head for successively supplying cleaning fluid from said supply port to said blower head ports, a plurality of nozzles carried by the blower head adapted upon rotation of the blower head to supply jets of cleaning fluid successively toward predetermined parts of the boiler to be cleaned, said blower head having a plurality of spirally arranged cleaning fluid conducting passages respectively connecting the said nozzles and blower head ports, means for automatically preventing the supply of cleaning fluid to such nozzles as are not directed to a predetermined portion of the boiler, and means for introducing a cooling fluid to at least one of the said spiral passages when their respective blower head ports are not in registration with said supply port.

17. A boiler cleaner comprising a body portion provided with a cleaning fluid conducting passage extending longitudinally thereof, a cleaning fluid discharge nozzle communicating with said passage and arranged to discharge a jet of cleaning fluid transversely of said body portion, said passage being constructed so that when the cleaning fluid is admitted thereto the said body portion will be subjected to a force substantially balanced.

ing the thrust resulting from said transverse discharge.

18. A boiler cleaner comprising a body portion provided with a cleaning fluid conducting passage extending longitudinally thereof, a cleaning fluid discharge nozzle communicating with said passage and arranged to discharge a jet of cleaning fluid transversely of said body portion, said passage being formed spirally and being so arranged that when the cleaning fluid is admitted thereto, the said body portion will be subjected to a force opposing the transverse thrust incident to said transverse discharge.
19. A boiler cleaner comprising a body portion provided with a plurality of cleaning fluid conducting passages extending longitudinally thereof, cleaning fluid discharge nozzles communicating with said passages respectively and arranged to discharge jets of cleaning fluid transversely of said body portion, said nozzles varying in angularity relative to the axis of said body portion and said passages being constructed so that when the cleaning fluid is admitted thereto, said body portion will be subjected to a force opposing the transverse thrust incident to said transverse discharge.

20. A boiler cleaner provided with a body portion having a cleaning fluid discharge nozzle arranged to produce a reaction thrust transversely of said body portion, and means for supplying cleaning fluid to said nozzle, said means being arranged upon the supply of cleaning fluid to the nozzle to substantially balance the said reaction thrust.

21. A boiler cleaner comprising a casing having a cleaning fluid inlet and a cleaning fluid supply port, a blower head having a plurality of ports, means for moving the blower head relative to the casing for successively supplying cleaning fluid from said supply port to said blower head ports, a plurality of nozzles communicating through passages with said blower head ports respectively, said nozzles varying in angularity relative to the axis of the blower head and being arranged to discharge transversely of the blower head, and said passages being constructed so that when the cleaning fluid is admitted thereto the said blower head will be subjected to a force opposing the transverse thrust, incident to said transverse discharge.

22. A boiler cleaner provided with a body portion having a cleaning fluid discharge nozzle arranged to discharge transversely of said body portion, and means for supplying cleaning fluid to said nozzle, said means being adapted upon supply of cleaning fluid to the nozzle to substantially balance the reaction thrusts incident to said transverse discharge.

23. A boiler cleaner provided with a body portion having a cleaning fluid discharge nozzle arranged to discharge obliquely to the

axis of said body portion, said body portion having a cleaning fluid conducting passage arranged to substantially balance the transverse thrust incident to said oblique discharge upon passage of cleaning fluid therethrough, said body portion being constructed with a piston, and means for supplying cleaning fluid to act on said piston to substantially balance the longitudinal thrust incident to said oblique discharge.

24. A boiler cleaner comprising a casing having a cleaning fluid inlet and a cleaning fluid supply port, a blower head having a plurality of ports, means for moving the blower relative to the casing for successively supplying cleaning fluid from said supply port to said blower head ports, a plurality of nozzles communicating through passages with said blower head ports respectively, the arrangement of said nozzles being such as to produce a reaction thrust on the blower head longitudinally thereof upon discharge of cleaning fluid therefrom and cleaning fluid operated means dependent upon the passage of cleaning fluid to said nozzles for substantially balancing the blower head.

25. In combination, a boiler cleaner having a cleaning fluid discharge nozzle, means including a movable member for varying the direction of the discharge nozzle, and means dependent upon the first said means for supplying a lubricant to said movable member.

26. In a boiler cleaner, a blower head having a cleaning fluid discharge nozzle, means including a shaft for imparting rotation to said blower head, a bearing for said shaft, and means actuated by said first named means for supplying a lubricant to said shaft and bearing.

27. In combination, a boiler cleaner having a cleaning fluid discharge nozzle, means including a movable member for varying the direction of the discharge nozzle, and means dependent upon the first said means for supplying a lubricant to said movable member, said last named means including a lubricant container and a relatively movable plunger operating in said container.

28. A boiler cleaner comprising a casing having a cleaning fluid inlet and a cleaning fluid supply port, a blower head having a plurality of ports, means for moving the blower head relative to the casing for successively supplying cleaning fluid from said supply port to said blower head ports, a plurality of nozzles communicating through passages with said blower head ports respectively, said blower head having a bearing in said casing, and means dependent upon the movement of the blower head relative to the casing for lubricating said bearing.

29. A boiler cleaner comprising a casing having a cleaning fluid inlet and a cleaning fluid supply port, a blower head having a plurality of ports, means for rotating the

- blower head relative to the casing for successively supplying cleaning fluid from said supply port to said blower head ports, a plurality of nozzles communicating through passages spirally formed around the axis of said rotation with said blower head ports respectively, said blower head having a bearing in said casing, and means dependent upon the rotation of the blower head relative to the
- 5 casing for lubricating said bearing.
30. A boiler cleaner comprising a nozzle adapted to discharge a jet of cleaning fluid for cleaning the tube sheet of a locomotive boiler, means for moving said nozzle to vary the direction of discharge of said jet of cleaning fluid, relatively stationary means affording a bearing for said moving means, and means dependent upon movement of the nozzle for forcibly supplying a lubricant to said
- 15 bearing.
31. A boiler cleaner comprising a nozzle adapted to discharge a jet of cleaning fluid, means for moving said nozzle to vary the direction of discharge of said jet of cleaning fluid, relatively stationary means affording a bearing for said movable means, and movable means operable upon movement of said nozzle for forcibly supplying a lubricant to said bearing.
- 20
32. The combination with a blower element having a cleaning fluid discharge nozzle, of a cleaning fluid conducting passage for said nozzle, the said passage being so arranged that the cleaning fluid as it flows through the
- 25
- 35 passage creates a force which tends to resist the reaction of the cleaning fluid escaping from the said nozzle.
33. A boiler cleaner including in combination a fixed casing, a blower head mounted at one end on the said casing, the said blower head being rotatable about its longitudinal axis, nozzles arranged at the free end of the blower head, and spiral passages in the said head for conducting cleaning fluid to the
- 40
- 45 said nozzles, the said spiral passages being arranged to have their inlets and outlets on opposite sides of the longitudinal axis of the said blower head.

In testimony whereof we affix our signatures.
